Primary Examiner — Katrina N Gonzalez

CLAIM

The ornamental design for a feeder, as shown and described.

DESCRIPTION

FIG. 1 is a front perspective view of a feeder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof;

FIG. 10 is an enlarged detail view of area 10 in FIG. 2 thereof;

FIG. 11 is an enlarged detail view of area 11 in FIG. 2 thereof; and,

FIG. 12 is an enlarged detail view of area 11 in FIG. 7. The broken lines in the drawings illustrate the portions of the feeder, which form no part of the claimed design.

The dash-dot-dash broken lines represent the boundaries and indicator of the enlarged view that form no part of the claimed design.

1 Claim, 12 Drawing Sheets
